UNITED STATES PATENT OFFICE.

ROBERT NORRIS, OF WASHINGTON, DISTRICT OF COLUMBIA.

WINDOW-WEATHERPROOFING AND SASH-ADJUSTING MEANS.

Application filed April 2, 1927. Serial No. 180,603.

This invention relates to certain new and novel improvements in windows provided with sliding sash frames, and has special reference to the novel construction of the 5 sash frames and their adjusting and locking means combined with the window frames, whereby when the sash frames are in their closed and locked position an absolutely airtight and weather-proof structure is provided, and at the same time the invention 10 includes means whereby the sash-frames may be easily manipulated so as to furnish the desired amount of ventilation without ornating a direct draft, and said novel features 15 constitute improvements on the Letters Patent granted to me under date of May 25, 1920, No. 1,341,434.

The main object of the invention is to provide a simple, durable, economical and 20 thoroughly efficient window frame, and sliding sashes fitted therein, in connection with novel sash adjusting and locking means, so constructed and arranged that wind, dust, rain, or other foreign matter will be completely excluded when the sashes are locked 25 in closed position, thereby constituting a weather-proof window and preventing the sashes from rattling.

Another object of this invention is to 30 furnish novel sash adjusting and locking means adapted to be used for ventilating purposes, which will permit the entrance into a room of a sufficient supply of fresh air without producing a direct draft, or in 35 any other manner subjecting the occupants to inconvenience or discomfort, and at the same time so locking the respective sashes in their adjusted positions as to securely retain them in such positions, when subjected 40 to sudden gusts of wind, the accidental breakage of the sash cords, or attempted removal by an unauthorized person from the outside of the window.

Another object of the invention is to provide 45 means to adjust both the upper and lower sashes with relation to each other and retain them in their adjusted or ventilating positions.

Another object of my invention is to provide 50 novel locking and interlocking means connected with the sashes and window frame, whereby the parts are removably and detachably secured together in their proper relative positions.

Further objects of the invention are to 55 so construct the window frame and sashes,

that the top rail of the upper sash and the lowermost rail of the lower sash will normally remain out of contact with the heading at the top of the window frame and the sill 60 of said frame respectively, and the offset formed on the inner face of each meeting rail will also normally be out of contact with each other, in order to permit further and closer adjustment of said parts with relation to each other by the use of the locking means secured to the meeting rails, and thereby compensate for the wear caused by the frictional contact of the several bevelled parts with respect to each other, and to 70 provide a parting strip formed of two members, the upper member being fixedly secured to the window frame and its lower member detachably secured to the said frame. 75

The foregoing and such other objects as may appear from the ensuing description are attained by the novel features of construction, arrangement, combination and location of the parts hereinafter more fully described, illustrated in the accompanying drawings, and particularly pointed out in claims appended hereto, it being understood that slight changes in the form, proportions and minor details of the construction may be resorted to without departing from the spirit or sacrificing any of the advantages of the invention. 80

In the accompanying drawings forming a part of this specification it will be seen that: 90

Figure 1 is a perspective of the improved means embodying my invention.

Fig. 2 is a central sectional elevation showing the sashes in closed position.

Fig. 3 is a similar view showing the lower 95 sash swung inwardly into a ventilating position, but showing a slightly modified form of frame.

Fig. 4 is a similar view showing the upper sash swung outwardly into a ventilating position. 100

Fig. 5 is a similar view of window frame with the sashes removed therefrom.

Fig. 6 is an end elevation of both the lower and upper sashes and the lower half 105 of the parting strip removed from the window frame.

Fig. 7 is a detail partly in section and partly in side elevation showing the means for securing the upper sash in its outward 110 position.

Fig. 8 is a detail sectional perspective

taken through a portion of the window frame and the upper sash.

Fig. 9 is a detail perspective showing the securing means attached to the upper 5 edge or end portion of the upper sash.

Fig. 10 is a similar perspective showing the securing means swung outwardly and exposing the sash cord securing means.

Fig. 11 is a plan partly in transverse 10 section showing the sash meeting rails and the window sash securing means attached thereto.

Fig. 12 is a detail vertical section taken 15 through the lower portion of the window casing and lower sash showing a portion of the window casing in side elevation.

Fig. 13 is a detail vertical section taken through the lower portion of the window frame showing the lower end of the parting 20 rail in side elevation.

Fig. 14 is a detail vertical section showing the means for securing the upper hinged section to the lower fixed stop section of the window frame, and

25 Fig. 15 is a detail sectional elevation showing the construction of and the means for holding the upper sash in its outward position.

Similar numerals of reference are employed to designate like parts throughout the several views of the drawings.

In the embodiment of my invention as illustrated, the numeral 1 indicates the window frame provided with the necessary 30 pulleys, sash cords 2, and sash weights 3, said pulleys being preferably secured within the housings 4 rigidly secured to the upper end or heading 5 of the window frame at each side thereof, while 6 and 7 designate the 35 respective slideways for the upper and lower sashes.

By reference to Figs. 2 and 3, it will be seen that the upper end portion of the window frame is provided with a stationary 40 beveled cross-bar 8 adapted to contact with a complementary beveled cross-bar 9 forming the upper end of the upper sash frame 10, and the lower cross-bar or meeting rail 11 of said upper sash is beveled at 12 and 45 13, so as to contact with the complementary beveled cross-bar 14 constituting the upper end or meeting rail of the lower sash frame 16, each of said meeting rails being 50 formed with a shouldered portion or offset 55 17 and 18, respectively, extending the entire length of each rail and adapted to overlap each other when the meeting rails are in close contact, while the cross-bar 18' forming the lower end portion of the lower sash 60 is so beveled as to rest in contact with the complementary beveled portions 20 and 21 formed on the inner face of the stool 22 and sill 23, respectively, with the downwardly 65 extended lip portion 24 formed on said cross-bar 18' overlapping the shoulder por-

tion 25 formed in the sill 23 and serving as a sealing medium to prevent the entrance of air or moisture, said meeting rails being preferably provided with two pairs of suitable locking means 26, whereby when 70 the sashes are locked in their closed position, said sashes will be forced into such closed and rigid contact with each other and with the beveled surfaces of the window frame, due to the wedging action of the beveled 75 surfaces at the top and bottom of the window frame, and the meeting rails, as to effectually prevent the entrance of cold air, moisture, dust and other foreign matter, thus constituting a weather-proof window for cold climates, preventing rattling of the sashes during high winds, and dispensing with the use of weather strips, as will be readily obvious.

It will be perceived that the upper face of the cross bar 9 of the upper sash and the depending tongue 24 formed on the cross-bar 18', normally remain out of contact with the heading 5 and sill 23, respectively of the window frame, while the shoulders 17 and 18 formed on the meeting 80 rails also remain out of mutual contact, so that the said parts may be adjusted in closer relation with each other by the proper manipulation of the inclined locking means when the beveled portions shall have been 85 subjected to more or less shrinkage, warping and wear, thereby compensating for such shrinkage, wear, warping, etc.

In each of the upright side portions of the window frame is formed a longitudinal 90 groove in which is fitted a parting strip or rail composed of a stationary section 27, and a removable section 28, each of said sections being provided at their meeting ends with a complementary beveled or inclined portion 95 29, the lower end of the upper section of said strip or rail being provided with a recess formed centrally therethrough adapted to receive a centrally arranged rib or tongue 100 projecting from the upper end of the lower removable section 28, whereby the said sections will be securely locked together, when the removable section is placed in its proper position in alignment with the stationary section, the beveled or inclined meeting ends 105 29 permitting the ready removal and replacement of the detachable section when desired. As clearly shown in Fig. 8, each section of the parting rail or strip, is provided with a longitudinal integral lateral extension 110 forming a tongue 30, said tongue being disposed on opposite sides of the parting strips and the upper end of the tongue of the stationary section resting in contact with the inner upper face of the window frame and extending downward to a point in alignment 115 with the lower end of said section, while the lower section is provided with a similar tongue terminating at its upper end near the uppermost end of said lower section, and its 120

lower end terminating slightly above the upper face of the sill, said tongues being adapted to be suitably fitted into complementary grooves formed in the inner face of each upper side rail 31 of the upper sash, and the outer side face of each upright rail 32 of the lower sash, the grooves in the upper sash extending from the top thereof and terminating within the meeting rail, while the grooves formed in the lower sash extend from its bottom end and terminates within its meeting rail, said tongues of the parting strip or rail being so fitted within the grooves formed in the side rails of each sash as to permit the sash frames to freely slide upward and downward thereon, at the same time preventing the access of any cold air into a room owing to their construction and their relative position with respect to each other, and to the termination of the grooves at the points named within the sash frames, as will be readily understood.

As shown in Figs. 1, 3 and 4 it will be seen that the inner stop strip, at each side of the window frame is composed of an upper stationary section 33 and a lower hinged section 34, each hinged section being provided with a plurality of hinges, one leaf of each of said hinges being fixedly fitted within a recess formed in the inner face of the section and having a knob or headed pin 35 fixed thereto, with the other leaf thereof fixedly fitted into a recess formed in the face of the window frame, with an opening 36 formed therethrough, and leading to a recess of slightly larger diameter formed in the window frame for the reception of the knob or headed pin 35 when said section is in its closed position, each of said hinged sections being adapted to swing outward when it is desired to remove the sashes, or to ventilate the room by swinging the lower sash inward. By reference to Fig. 6, it will be seen that each face of the upright side rails 32 of the lower sash is provided with a plurality of elongated recessed portions each adapted to receive a fixed metallic plate having an opening 38 therethrough and adapted to cover a recess of slightly larger diameter than said opening for the reception of the knob or headed pin 35, for the purpose of locking the lower sash in a plurality of positions when it is swung inwards for ventilating purposes. Within a recess formed in the lower end portion of each of the stationary sections 33 is fixedly secured a small pulley 39 adapted to receive the sash cords, and thus prevent wear and friction on said cords when the lower sash is adjusted inwardly.

At each upper end face of the upper sash is fixedly secured within a recess formed in said face a metallic plate 40, as clearly shown in Figs. 9 and 10, adapted to cover the sash cord fastening socket 41 to protect said cord

from the weather and stamped within the outer face of said plate 40 is a curved recessed portion 42, said recess being larger at its outer end, from whence it converges gradually inward and terminates at its inner end with a semi-circular wall 43, and said plate is adapted to be seated within a recess 42' formed in the sash, which recessed portion 42 and wall 43 are adapted to engage with a headed pin or roller 44 fixedly secured at each side of the inner face of the window frame near its top portion, when the upper sash is adjusted outwardly for ventilation, thereby forming anchoring means for supporting the said upper sash in its outward position and preventing its accidental falling in the event of the parting of the sash cords, and its removal from the window by an unauthorized person.

It will be seen that said plate 40 is adapted to be swung outwardly on its fixed pivot pin or screw 41' for the purpose of removing the sash cord from its socket 41, only when the sash is removed from the window frame.

As shown in Figs. 11 and 15, the meeting rail of the upper sash is provided with a plurality of rods 45, one end of each rod having a globular portion resting within a socket 46 formed in the meeting rail, thereby forming a ball and socket connection and its other depending end portion 47 terminating with a slightly enlarged end 48, receivable within an enlarged recess also formed in the said rail, each of said recesses being covered by a metallic plate 49 and 50, each plate having an opening therethrough to receive the end portions of the rod, the opening in the plate 50 being of sufficient diameter to permit the enlarged end 48 to be lifted therefrom when properly guided.

It will be apparent that the outer stop strip at each side of the window frame is composed of a lower stationary section 51 and an upper hinged section 52, each hinged section being provided with a plurality of hinges, one leaf of each hinge being fixedly secured within a recess formed in the hinged section, and the other leaf fixedly fitted in a recess formed in the inner face of the window frame, said hinged sections being adapted to be swung outwardly when it is desired to swing the upper sash outwardly for ventilation, and at such time the end portion 47 of each of the rods 45 is lifted from its respective socket, and passed through the opening 47' formed in the outwardly extended member 53 of the metallic bracket 54, fixedly fitted within a recess formed in the inner face of the window frame and on the upper face of each stationary section 51, respectively, said extended member of the bracket serving to cover a recess 48' formed in the upper end portion of each stationary section of larger diameter

than the opening 47, and adapted to retain the enlarged end portion of a rod 45 within the recess thereby fixedly securing the upper sash in its outwardly, adjusted position, shown in Fig. 4, until it is desired to return said sash into alignment with the window frame, when it will be simply necessary to lift the ends of the rods from the recesses 48 and return them to their respective recesses formed in the meeting rail of the upper sash.

The inner face of each of the hinged upper sections 52 is provided with a recess 55 formed therein each serving when the sections are in closed position to be fitted over to cover and protect the headed pin or roller 44, and the lower end of each of said hinged sections is provided with a fixed beveled or round headed pin 56 which is adapted to be seated within the opening formed in the slightly beveled and yielding extended member 53 of the bracket 54, and thus secure the said sections when in their closed position, as shown in Fig. 14.

It will be seen that the lowermost end of the removable section of the parting rail or strip is fitted within a recess formed in the window sill while the tongue formed on the said strip or rail terminates slightly above said sill.

Having thus described my invention, what I claim and desire to secure by Letters Patent is:—

1. A window of the character described, comprising a frame, slidable and swingable sashes fitted therein, hinged inner stop sections secured to the lower portions of the jambs; hinged outer stop sections secured to the upper portions of the jambs, and a plurality of locking means carried by the hinged lower sections adapted to be fitted into the end faces of the lower sash to secure said sash in its inwardly adjusted positions.

2. A window of the character described, comprising a frame, slidable and swingable sashes fitted therein, hinged inner stop sections secured to the lower portions of the jambs, hinged outer stop sections adapted to be fitted into the end faces of the lower sash secured to the upper portions of the jambs, a plurality of locking means fixed to the lower hinged sections, and means secured to the outer end face of the upper sash adapted to engage with means secured to the upper portion of the frame for supporting said upper sash in its outward adjusted position.

3. A window of the character described, comprising a frame, slidable and swingable sashes fitted therein, hinged inner stop sections secured to the lower portions of the jambs, said hinged sections provided with a plurality of locking means, and a plurality of sockets formed in the outer end faces of the lower sash frame for the reception of said locking means, whereby said sash frame

is secured in its inwardly adjusted positions.

4. A window of the character described, comprising a frame, slidable and swingable sashes fitted therein, hinged inner stop sections secured to the lower portions of the jambs and provided with a plurality of locking means for securing the lower sash frame in its inwardly adjusted positions, means formed in the outer ends of said sash frame for engaging said locking means, hinged outer stop sections secured to the upper portions of the jambs, and means secured to the outer end faces of the upper sash for the reception of means carried by the jambs for supporting said upper sash in its outward adjusted position.

5. A window of the character described, comprising a frame, slidable and swingable sashes fitted therein, hinged inner stop sections secured to the lower portions of the jambs, each of said sections having a plurality of hinges, one leaf of each hinge being secured to a stop section and having a locking means fixedly secured thereto, means formed in the outer ends of the lower sash frame adapted to engage said locking means, and the other leaf of each hinge being fixedly secured to a jamb of the frame and having an opening therethrough leading to a recess formed in said frame for the reception of said locking means when the hinged sections are in their closed positions.

6. A window of the character described, comprising a frame, slidable and swingable sashes fitted therein, hinged inner stop sections secured to the lower portions of the jambs, and provided with a plurality of hinges fixedly secured thereto having fixed locking means formed thereon, a plurality of sockets formed on the outer end faces of the lower sash adapted to receive the locking means and secure the said lower sash in its inwardly adjusted positions.

7. A window of the character described, comprising a frame, slidable and swingable sashes fitted therein, hinged outer stop sections secured to the upper portions of the jambs, a fixed roller secured to the upper portions of a jamb of the frame, and means secured within the outer end face of the upper sash frame for the reception of said roller to support the said sash frame in its outward adjusted position.

8. A window of the character described, comprising a frame, slidable and swingable sashes fitted therein, hinged stop sections secured to the lower portions of the jambs and provided with a plurality of locking means adapted to hold the lower sash in its inward adjusted positions, means secured to said lower portions of the jambs of said frame for the reception of the locking means when said hinged sections are in their closed position, hinged outer stop sections secured to the inner upper face of the frame, and

means secured to the lower end of each last named section for holding them in their closed position.

9. A window of the character described, comprising a frame, slideable and swingable sashes fitted therein, a lower fixed jamb strip formed on each jamb of the frame provided with a socket in its upper end, hinged sections secured to the upper portions of the 10 jambs and each forming a movable upper jamb strip, the sections of the jamb strips adapted to be arranged in axial alinement, and means pivotally secured to the meeting rail of the upper sash adapted to rest in said 15 sockets for securing the upper sash in its outward adjusted position.

10. A window of the character described comprising a frame, slideable and swingable sashes fitted therein, hinged stop sections 20 secured to the lower portions of the jambs and provided with a plurality of locking means adapted to engage cooperating means in the lower sash to hold the latter in a plurality of inward adjusted positions, and 25 means carried by the upper sash for holding said sash in its outward adjusted position.

11. A window of the character described, comprising a frame, slideable and swingable sashes fitted therein adapted to be adjusted 30 in reverse directions, the upper sash being provided at each end face thereof with a pivoted recessed metallic plate, a roller fixedly secured to the said frame adapted to engage with said recessed plate, and 35 means carried by the meeting rail of said sash for securing the sash in its outward adjusted position.

12. A window of the character described, comprising a frame, slideable and swingable 40 sashes fitted therein adapted to be adjusted

in reverse directions, a pivoted recessed metallic plate secured to each outer end face of the upper sash adapted to cover the sash cord socket, a strip fixedly secured to the window jamb, a roller fixedly secured to each side of the said frame adapted to engage with the recessed plate, and means carried by the meeting rail of said upper sash adapted to engage with a recess formed in the upper end of the said strip for securing the said sash in its outward position. 45 50

13. A window of the character described, comprising a frame, slideable and swingable sashes fitted therein adapted to be swung in opposite directions, a strip secured to each 55 jamb, a plurality of rods secured to the meeting rails of the upper sash, each of said rods being formed with an enlarged end portion adapted to engage with a recess formed in the upper end of the respective one of said 60 strips and adapted to secure the said upper sash in its outward adjusted position.

14. A window of the character described, comprising a frame, slideable and swingable sashes fitted therein, hinged stop sections 65 secured to the lower portions of the jambs provided with a plurality of locking means adapted to engage with sockets formed in each end face of the lower sash frame, hinged sections secured to the upper portions of said jambs, each last named section being provided with a recess near its upper end, a metallic recessed plate secured to each upper end face of the upper sash adapted to engage with a roller fixedly secured to each jamb, and receivable in one of 70 75 said recesses, and means secured to the meeting rail of the upper sash for holding said sash in its outward adjusted position.

ROBERT NORRIS.
